TOY FOR DENTAL ENGINES

Charles J. Gardetto, Milwaukee, Wis.

Application August 15, 1947, Serial No. 768,755

5 Claims. (Cl. 46—122)

1

This invention relates to a toy applicable to a dental engine.

It is a primary object of the invention to provide a novel means for amusing a patient while he is undergoing dental treatment and diverting his attention from the work of the dentist. The objects will appear in more detail in connection with the following disclosure of the invention.

In the drawings:

Fig. 1 is a view in side elevation showing the 10 invention as it appears in use on a dental engine.

Fig. 2 is an enlarged detail view in front elevation of a toy embodying the invention.

Fig. 3 is a view showing the toy in rear elevation.

Fig. 4 is a detail view taken in vertical section through the toy and the cord of the dental engine.

Figs. 5 and 6 are enlarged detail views showing slightly modified embodiments of the invention.

Fig. 7 is an enlarged detail view partially in section and partially in perspective showing a further modified embodiment of the connection between the toy and the cord.

The dental engine chosen to illustrate the use of the invention comprises the usual articulated framework provided at its joints with pulleys, over which operates the cord 7 which serves as a belt to transmit power from the motor 8 to 30 the pulley 9 on the spindle of the handpiece.

The toy comprises any desired figure 10 cut from thin sheet rubber or the like and suitably decorated to represent, for example, the dog shown in Fig. 2, or the rabbit shown at 11 in Fig. 1. While it is not essential that rubber be used, I have found either natural or synthetic rubber to be ideal, inasmuch as great resilient flexibility is required in order that the toy may pass freely about the many pulleys traversed by the cord 7. In many instances, the cord passes through guides such as those shown at 12, and the pliability of the toy figure must be such that it will traverse these guides without any serious resistance to the movement of the cord or belt.

In cutting out each figure, an integral base or support 15 is provided to extend along the cord. There must also be some means for conveniently mounting the device on the cord, preferably without any necessity for severing or opening the belt.

I have found it convenient to provide, in the base portion 15 of the toy, two rows of staggered holes at 16 and 17 through which a light helical spring 18 may be laced and made to en-

2

circle the cord by rotating the helical spring, and thereby feeding it successively through the holes and about the cord.

If desired, I re-enforce the base about the 5 openings as suggested in Figs. 5 and 6. In Fig. 5, the holes 160 and 170 in the base 150 have been re-enforced by molding the base to provide an annular bead at 19 around each hole. In Fig. 6, the base and its apertures are exactly as shown in Fig. 4, but they have been re-enforced by cementing or otherwise laminating a separate ply 20 to the base, the re-enforcing ply having registering apertures at 21 and 22.

The resilient and flexible sheet stock from 15 which the toy is preferably blanked out should desirably be just sufficiently stiff to be reasonably self-supporting and to resume its upright position after passing through a guide or about a pulley. Yet, as above stated, it should be so 20 limp as to be deformable with the greatest of ease so that it offers no substantial resistance in passing the pulleys or guides. A thin sheet of dental rubber is ideal. The helical spring used as a connector should also be very light 25 and very flexible.

Fig. 7 exemplifies another of the numerous attaching means which may conveniently be employed. Eyelets or rivets 23, passing at intervals through the base of the sheet stock 15 comprising the toy, may hold thereto individual spring hooks 25, each of which is formed to partially encircle the dental engine cord 7. These hooks may be snapped over the cord for lateral engagement therewith much more easily and speedily than the spring 18 can be wound thereon and laced through the openings 16, 17. Since there is no connection between successive hooks 25, the inherent flexibility of the cord 7 is not impaired at all.

Where the required conditions of flexibility are taken into consideration, it will be found that the toy interferes in no way with the ordinary routine use of the dental engine. Yet, the movement of the toy in the circuitous path which it 45 follows with the cord or belt is a source of continued fascination to patients, particularly to children, who never seem to tire of watching a dog chase a rabbit (for example) upon the circuitous path of the belt.

I claim:

1. A toy applicable to the cord or belt of a dental engine to pass freely therewith about the pulleys of such engine, said toy comprising a thin sheet of rubber having just sufficient body to resume its form after deformation, said rubber

sheet having a mounting portion applicable to the cord or belt and provided with spaced apertures, and a connector comprising a wire traversing the apertures and arcuately shaped to encircle said cord.

2. The combination set forth in claim 1 in which the wire comprises a helix traversing the apertures of the mounting portion a plurality of times with intervening encirclement of the belt.

3. The combination set forth in claim 2 in which the apertures are marginally re-enforced.

4. The combination with the operating belt cord of a dental engine, of a toy mounted thereon to partake of the movement of said cord, said toy comprising a resiliently flexible sheet of rubber having a figure portion and a mounting portion, the mounting portion extending along the cord and being provided with staggered rows of apertures, and a flexible connector comprising a wire helix placed through the apertures and encircling the cord for attaching the toy to the cord.

5. The combination set forth in claim 4 in further combination with a second light toy upon the cord in spaced relation to the toy first mentioned, whereby the movement of the cord makes

one of the toys appear to chase the other upon the path of the cord.

CHARLES J. GARDETTO.
